Primary Examiner — Patricia A Palasik*(74) Attorney, Agent, or Firm* — Raymond Chan**CLAIM**

The ornamental design for an extendable platform of woodworking machinery, as shown and described.

DESCRIPTION

FIG. 1 is a perspective view of an extendable platform of woodworking machinery showing my new design.

FIG. 2 is a second perspective view of the extendable platform of woodworking machinery in a folded position;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a perspective view showing the extendable platform arranged with a woodworking machine; and,

FIG. 10 is a perspective view showing the extendable platform arranged with a woodworking machine in a folded position.
